(57) **CLAIM**

The ornamental design for the novelty device, as shown and described.

DESCRIPTION

FIG. 1 is a perspective view of the novelty device;

FIG. 2 is a front elevational view thereof;

FIG. 3 is a right side elevational view thereof with the left side elevational view being the same except for the staggered heights of the upper tips;

FIG. 4 is a top plan view thereof; and,

FIG. 5 is a bottom plan view thereof.

An alternative embodiment of my design is similar to the design embodiment shown in FIGS. 1-5, but made with a translucent material.

1 Claim, 3 Drawing SheetsFIG. 1

FIG. 2

FIG. 3

FIG. 4

FIG. 5
